S. L. MORGAN

LOCK

Filed May 12, 1923

Inventor:
Stephen L. Morgan,
by his attorney
Charles R. Searle.

UNITED STATES PATENT OFFICE.

STEPHEN L. MORGAN, OF SKANEATELES, NEW YORK.

LOCK.

Application filed May 12, 1923. Serial No. 638,607.

To all whom it may concern:

Be it known that I, STEPHEN L. MORGAN, a citizen of the United States, residing at Skaneateles, in the county of Onondaga and

5 State of New York, have invented a certain new and useful Improvement in Locks, of which the following is a specification.

The invention relates to locks of the permutation type having a plurality of rotatable disks serving as tumblers which release when brought into prearranged relation with certain fixed portions of the lock.

10 The object of the invention is to provide a lock of this character which shall be simple and economical in construction, easily operated and reliable.

15 A further object is to provide means whereby the mechanism of the lock is easily accessible for changes in the combination when unlocked, and in which such access is reliably prevented when in the locked condition.

20 The invention consists in certain novel features and details of construction and arrangements of parts by which the above and other objects are attained, to be hereinafter described and claimed.

25 The accompanying drawings form a part of this specification and show the lock as located on the instrument board of an automobile, and adapted to serve in breaking the ignition circuit when in the locked condition and thus prevent unauthorized operation of the car.

30 Figure 1 is a front elevation of the exposed portions of the lock.

35 Figure 2 is a vertical central section taken on the line 2—2 in Figure 1, partly in elevation, showing the parts in the unlocked condition.

40 Figure 3 is a vertical transverse section taken on the line 3—3 in Figure 2, seen in the direction indicated by the arrows and partly in rear elevation.

45 Figure 4 is a vertical transverse section taken on the line 4—4 in Figure 2 and partly in rear elevation.

50 Figure 5 is a vertical section and elevation corresponding to portions of Figure 2, showing the parts in the locked condition.

55 Figure 6 is a plan view of the fixed stud on which the parts are mounted.

Figure 7 is a corresponding view of a sleeve adapted to slide on the stud.

55 Figure 8 is a face view of one of the locking disks alone.

Figure 9 is a face view of the dial by which the disks are brought into the desired relation to unlock.

Similar reference numerals indicate the 60 same parts in all the figures.

On the back of the instrument board 10 of the automobile, is a cup-shaped case 11 having a flange 12 by which it is secured to the board by screws 13 extending into the 65 flange from the front face, that is, the face of the board presented toward the operator.

A centrally located cylindrical stud 14 firmly mounted on the back of the case by riveting or otherwise, extends forwardly 70 therein and supports the mechanism of the lock. The stud is inclosed in a sleeve 15 arranged to slide longitudinally thereon but held against rotation by a feather or fin 16 fixed on the stud, engaged in a longitudinal 75 slit 17 in the sleeve, and projecting radially beyond its surface. The fin is notched as at 18, 19 and 20 to a depth reaching the surface of the sleeve to provide a series of spaced projections protruding above the 80 sleeve. Inclosing the sleeve is a series of disks 22, 23 and 24 rotatably mounted thereon and adapted when in coincidence with their respective notches 18, 19 and 20 to be 85 freely rotatable. Each has an internal recess 25 matching the projections 21 of the fin, and all are held on the sleeve in proper spaced relation by fixed washers 26 carried by the sleeve.

Thus arranged, the disks may be moved to 90 coincide with the notches by sliding the sleeve inwardly in which position they may be rotated and engaged with the fin to hold the sleeve against an outward movement, and when turned to present their recesses 25 95 in alinement with the projections 21 of the fin, permit the sleeve to slide outwardly on the stud, in the unlocked condition. This outward movement is effected automatically by a helical spring 27 encircling the stud 14 100 at its base and abutting at one end against the inner end of the sleeve and at the other end against the face of the case 11. The outer end of the sleeve is closed and has a peripheral flange or rim 28 and is provided 105 with a button 29 by which it may be easily thrust inwardly to the locking position.

The forward end of the sleeve is inclosed by a tubular collar 30 which extends through the plate 31 at the front, secured to the front face of the instrument board 10 110 by screws 32 and serving to cover the open-

ing therein corresponding to the interior of the case.

On the protruding end of the collar 30 is an annular knurled head 33 adapted to be 5 easily grasped by the finger and thumb of the operator in rotating the collar, and the latter is held in place axially on the sleeve between the rim 28 and the forward disk 24, and is recessed annularly on its interior 10 at the rear to clear the fin 16 in all positions. Thus mounted the collar moves with the sleeve in its axial sliding movements and is rotatable thereon.

On the collar 30 within the case 10 is a 15 flange 34, preferably of greater diameter than the disks 22, 23 and 24, provided with a pin 36 projecting on its inner face, so located as to strike a similar pin 35 on the outer face of the outer disk 24 and rotate 20 the latter. Similar pins 37 on the faces of the disks 22 and 23 transfer the rotatory movement to those disks in the usual manner as will be understood.

Loosely mounted on the collar 30 between the flange 34 and plate 31 is a dial 38 bearing on its outer face figures or letters by which the disks are set to unlock; the dial is held close to the plate 31 by lugs 39 on the latter extending over the peripheral 30 margin of the dial, permitting its rotation while presenting its figures at a window 40 in the plate 31 through which they may be read. The dial is compelled to rotate with the flange 34 by long arms 41 on the dial extending loosely through holes 42 in the flange, thus permitting the latter to slide toward and from the dial while maintaining connection therewith in all positions.

The lock as shown is arranged to control 40 the ignition system of an automobile; when the sleeve 15 and collar 30 with the disks 22, 23 and 24 are thrust inwardly and the latter engaged in the notches of the fin 16, the ignition circuit is broken and the automobile cannot be operated, and when the 45 sliding parts are moved outwardly by the force of the spring 27 the circuit is again completed. The switch operated by these 50 sliding movements may be variously constructed; as shown in Figure 2 it comprises a lever 43 pivotally mounted on an insulating block 44 and having an insulated end 45 held in yielding contact with the face of the innermost washer 26 by a spring 46. The lever carries a knife 47 adapted to enter 55 between the leaves 48 of a fixed electrode mounted on an arm 49 secured to the block 44. A rearward movement of the washer breaks the contact which is automatically 60 reestablished when the washer again moves forward.

As before stated, the dial may bear any arrangement of letters or figures by which the disks may be set to bring their recesses 65 25 into alignment with the fin 16 in the

unlocking operation, but for convenience in memorizing the unlocking combination the usual clock dial with its numerals from 1 to 12 is preferred and the dial is thus shown.

The method of operation is the usual one employed in locks of this type and need not be specifically described; by turning the knurled head 33 the required number of times and in alternating directions to present the predetermined numbers at the window 40, the sleeve 15 and its connections will be urged forward by the spring 27 to reengage the switch 43 49.

In order to permit the operator to change 80 the combination to numbers of his own selection, each disk is provided with a series of tapped holes 50 adapted to receive the screwthreaded ends of the pins 37 to conform to such selected numbers.

By removing the screws 32 of the plate 31 when the lock is in the unlocked condition, the plate, with the sleeve 15 and its connections may be withdrawn from the stud 14 and removed from the case for resetting the combination or other purpose and again replaced, but it will be noted that in the locked position the knurled head 33 lies closely against the plate 31, and by reason of the engagement of the sleeve with the 90 fixed stud, the plate cannot be removed, and tampering with the switch or wires within the case 10 is effectually prevented.

By engaging the screws 13 which join 100 the case 11 to the board 10 from the front of the latter, the heads of the screws lie concealed beneath the plate 31 and the case is thus held against removal until the plate is first removed.

Although the mechanism is shown as arranged to protect the ignition system of an automobile, it will be understood that the lock will serve successfully in other situations and for other purposes to which it may be adapted.

I claim:

1. In a lock of the character set forth, a case, a stud fixed therein and having a notched fin, a sleeve having an open slit and adapted to slide axially on said stud and to engage said fin, a series of disks rotatably mounted on said sleeve and having recesses adapted in one position to register with said fin and permit such sliding movement, a plate covering said case, a collar rotatably mounted on said sleeve to slide therewith, projecting through said plate and having a head, and means operated by said collar for turning said disks, said head arranged to lie against said plate and hold the latter against removal when said sleeve is in the locked condition.

2. In a lock of the character set forth, a case, a stud fixed therein and having a notched fin, a sleeve having an open slit

- and adapted to slide axially on said stud and to engage said fin, a series of disks rotatably mounted on said sleeve and having recesses adapted in one position to register with said fin and permit such sliding movement, a plate covering said case, a collar rotatably mounted on said sleeve to slide therewith, projecting through said plate and having a head, a flange on said collar 10 within said case, means on said flange for turning said disks, a dial rotatably mounted on said collar and means for holding it adjacent said plate, and connecting means from said dial to said flange whereby 15 rotatory motion of said flange is communicated to said dial in all positions of said flange.
3. In a lock of the character set forth, a fixedly mounted case, a stud fixed therein 20 and held against movement and having a notched fin, a sleeve adapted to slide axially directly on said stud and having an open slit receiving said fin, a series of disks rotatably mounted on said sleeve and arranged 25 to engage the notches of said fin when said sleeve is thrust inwardly to present said disks to such notches, and a spring for thrusting said sleeve outwardly.
4. In a lock of the character set forth, a case closed at the rear, a stud fixed therein 30 and having a notched fin, a plate covering the open front of said case, a sleeve extending through said plate and inclosing said stud, arranged to slide axially thereon and having an open slit receiving said fin, 35 a series of disks rotatably mounted on said sleeve and arranged to engage the notches of said fin, a circumferential rim on the outer end of said sleeve, a collar rotatably mounted on said sleeve, arranged to slide 40 therewith and extended through said plate, and held against axial movement relatively to said sleeve by said rim, a flange on said collar within said case adapted to operate said disks, and a head on said collar arranged 45 to lie against said plate and hold the latter against removal when said sleeve is in the locked position.

In testimony that I claim the invention above set forth, I affix my signature hereto. 50

STEPHEN L. MORGAN.
